CLAIM

We claim the ornamental design for a portable terminal, as shown and described.

DESCRIPTION

FIG. 1 is a front perspective view of a portable terminal according to the present invention.

FIG. 2 is a front view of the portable terminal of FIG. 1. FIG. 3 is a rear view of the portable terminal of FIG. 1. FIG. 4 is a left side view of the portable terminal of FIG. 1. FIG. 5 is a right side view of the portable terminal of FIG. 1.

FIG. 6 is a top view of the portable terminal of FIG. 1; and, FIG. 7 is a bottom view of the portable terminal of FIG. 1. The broken lines and unshaded portions contained within broken lines depict exemplary elements of the portable terminal that are shown for illustrative purposes only and that form no part of the claimed design.
